ENCLOSED CIRCUIT INTERRUPTER

Max Hüber, Berlin-Siemensstadt, and Albert Dahms, Berlin, Germany, assignors to Westinghouse Electric & Manufacturing Company, East Pittsburgh, Pa., a corporation of Pennsylvania

Application June 2, 1939, Serial No. 277,068
In Germany June 2, 1938

17 Claims.

(Cl. 200—50)

The invention relates to circuit interrupting devices in general, and more particularly to circuit breakers, switches or motor starters which are mounted in enclosing housings for industrial application, and which are manually operable from outside of the enclosing housing by an operating handle on the housing.

Considerable difficulties have been encountered with some of the known types of enclosed circuit interrupters which are equipped with an operating handle on the openable cover of the enclosing housing. One difficulty has been that the operating handle on the cover cannot effect an operative engagement or connection with the circuit interrupter handle unless these handles are in corresponding positions when the cover is closed. Another difficulty is that the insulating handle of the circuit interrupter is apt to be broken or damaged when the cover is slammed shut. Also the structure for effecting connection between the interrupter handle and the operating handle on the cover are more complicated and expensive than is desired, thus increasing the total cost of the complete device.

An object of the present invention is the provision of an enclosed circuit interrupter operable by an operating handle on the openable cover and which obviates the disadvantages mentioned above of the prior art structures.

Another object of the invention is the provision of an enclosed circuit interrupter of the class described in which operative engagement or connection between the operating handle on the cover and the circuit interrupter handle can be easily effected after the cover is closed even though the handles are not in corresponding positions when the cover is closed.

Another object of the invention is the provision of an enclosed circuit interrupter in which the operative connection between the operating handle on the cover and the interrupter handle can be established when the cover is closed and the handles are in non-corresponding positions, merely by moving the operating handle to a position corresponding to that of the interrupter handle.

Another object of the invention is the provision of an enclosed circuit interrupter in which the means for effecting an operative connection between the operating handle on the cover and the insulating circuit interrupter handle is of such construction as to prevent breakage of the interrupter handle when the cover is slammed shut.

Another object of the invention is the provision

of an improved enclosed circuit interrupting device that is simple, reliable in operation, and inexpensive to manufacture.

The novel features that are considered characteristic of the invention are set forth in particular in the appended claims. The invention itself however, both as to structure and operation together with additional objects and advantages thereof will be best understood from the following detailed description of one embodiment thereof when read in connection with the accompanying drawing in which:

Figure 1 is a vertical sectional view of an enclosed circuit interrupter constructed in accordance with the invention,

Fig. 2 is a plan view of the enclosed interrupter, and

Fig. 3 is a vertical sectional view similar to Fig. 1, showing the circuit interrupter handle and the operating handle in non-corresponding position to illustrate the manner in which they may be operatively connected by moving the operating handle.

Referring to the drawing, the reference numerals 5 designates a protecting housing for enclosing a circuit interrupter 7. The housing 5 is preferably constructed of sheet metal and is provided with an openable cover 9 of the same material, which is hinged to one side of the housing by a pair of hinges 11. The housing 5 and its cover 9 serve to protect the circuit interrupter 7 and any other electrical devices which may be mounted in the housing from dust, dirt and other deleterious materials usually encountered in industrial plants. The cover may be swung to open position to permit access to be had to the electrical devices within the housing; and this cover is adapted to be locked in closed position by a suitable latching or locking device 13.

The circuit interrupter 7 may be a circuit breaker, switch or manual motor starter of any known construction having a movable actuating handle or lever. The circuit interrupter 7 shown is contained within its own casing 15, and is provided with an oscillatable actuating handle 17, preferably of insulating material, that is movable about a pivot to opposite "off" and "on" positions to open or to close the circuit controlled thereby. The actuating mechanism (not shown) of the interrupter is preferably of the type which is automatically operable upon overloads of predetermined magnitude and duration to effect opening of the contacts of the interrupter, and the mechanism is resettable after an automatic opening operation. There are a number of known circuit

breakers of this general type, one, for example, being fully described in Patent 2,048,114 to H. S. Gano and H. P. Dorfman, July 21, 1936, assigned to the assignee of the present invention.

An operating handle 19 is rotatably mounted on the cover 9 to provide for operating the interrupter 7 from outside the housing 5 when the cover 9 is closed. The handle 19 is rotatable to "off" and to "on" positions corresponding to "off" and "on" positions of the interrupter handle 17 and is adapted to move the interrupter handle to its various operating positions through the agency of a separable connecting means which will be hereinafter described. The cover 9 is provided with suitable indicia such as "on" and "off" which cooperate with an index mark 21 on the operating handle 19 to indicate the operating positions of the handle.

The operating handle 19 is rotatably mounted on the cover 9 by means of a shaft 23 secured to the handle which extends through an opening in the cover 9 and through a bushing or bearing 25 secured to the underside of the cover 9, the inner end of the shaft 23 projecting beyond the bearing 25.

The opening through which the shaft 23 extends is preferably packed in any suitable manner to prevent the entrance of dust or dirt into the housing at this point. The edges of the side and end walls of the cover 9 are slightly offset and are adapted to overlap and fit relatively close against the edges of the side and end walls of the housing 5 to provide a substantially dust and dirt proof joint therebetween when the cover 9 is in closed position.

The separable connecting means which serve to provide an operative connection between the operating handle 19 and the interrupter handle 17 when the cover is closed whereby rotation of the operating handle to "on" or "off" positions affects movement of the interrupter handle to corresponding operating positions to operate the interrupter, comprises a crank arm 27 which is rigidly secured to the inner end of the shaft 23, and a connecting member 29 carried by the circuit interrupter handle 17. The crank is keyed to the shaft 23 for rotation therewith and is held in mounted position on the shaft by the nuts 28.

The connecting member 29 has an integral yoke 31 at its upper end, the legs of which straddle the sides of the interrupter handle 17. A pivot pin 33 extends transversely through the circuit interrupter handle 17 and is engaged in aligned openings in the legs of the yoke 31 to pivotally connect the member 29 to the interrupter handle for movement therewith. The connecting member 29 is provided with a downwardly extending portion which is cylindrically arched, as indicated at 35, and which is provided with a transversely extending slot 37 midway between the ends of the cylindrically arched portion 35. The transverse slot 37 is adapted to receive an inwardly extending crank pin 39 formed integral with the end of the crank 27 to effect an operative connection between the operating handle 19 and the interrupter handle 17 when the cover is in closed position.

The connecting member 29 is yieldably movable about its pivot axis 33 inwardly away from the cover 9, and is biased outwardly against the crank pin 39 when the cover is closed by means of a leaf spring 41. One end of the leaf spring 41 is rigidly secured to the connecting member 29 by a pair of rivets 43, and the opposite end extends inwardly and abuts the casing 15 of the

circuit interrupter 7. This structure of the connecting member 29, including its connection to the circuit interrupter handle, its cylindrically arched portion 35 and the spring 41 permit the 5 crank pin 39 to be engaged in the slot 37 to effect an operative connection between the handles after the cover is closed by manual movement of the operating handle 19 to a position corresponding to that of the interrupter handle 17. Thus the operative connection between the handles can be established irrespective of the difference in their positions when the cover is closed. The structure of the connecting means also prevents breakage of the insulating interrupter handle 17 when the cover 9 is slammed shut. This results from the fact that impacts resulting from slamming of the cover when the crank pin 39 is not in alignment with the slot 37 are not transmitted directly to the interrupter handle 17 but merely result in the connecting member 29 being depressed against the resiliency of the spring 41.

Referring to Fig. 2, the operation of the device is briefly as follows. With the crank pin 25 39 operatively engaged in the slot 37, let it be assumed that it is desired to operate the circuit interrupter to the "off" position. The operating handle 19 is rotated in a clockwise direction from the "on" position shown in Fig. 2 to a 30 position in which the index 21 aligns with the word "off" on the cover 9. This movement of the operating handle 19 causes similar clockwise movement of the crank 27 and crank pin 39. The crank pin 39 being engaged in the slot 37 of the connecting member 29, clockwise movement of the crank pin causes the connecting member 29 to be moved downwardly in a straight line to effect downward movement of the circuit interrupter handle to its "off" position opposite to that of its "on" position shown in Fig. 2. To 35 close the interrupter the operating handle 19 is moved from its "off" position back to the "on" position shown in Fig. 2. This movement of the operating handle causes the crank pin 39 to move the connecting member 29 upwardly in a straight line to cause movement of the circuit interrupter handle upwardly from its "off" to its "on" position. The transverse slot 37 permits straight line movement of the connecting element 29 when the operating handle is rotated in either direction.

When the cover is swung to open position, the crank pin 39 is withdrawn from the slot 37 and moves with the cover to open position. When 55 the cover is closed, the crank pin 39 will reengage in the slot 37 if the operating handle 19 is in a position corresponding to that of the interrupter handle 17 at the time the cover is closed. However, if the operating handle 19 happens to be in a different position from that of the interrupter handle 17, even in a complete opposite position therefrom, the operative connection between the handles may be readily established after the cover is closed by merely 60 moving the operating handle to a position corresponding to that of the interrupter handle. This movement of the operating handle causes the crank pin 39 to ride up the cylindrically arched surface of the connecting member 29 depressing that member against the action of the biasing spring 41, as shown in Fig. 3. As soon as the crank pin reaches a position of alignment with the slot 37, the spring 41 snaps the connecting member 29 outwardly causing the slot 37 to en-

gage the crank pin 38 and thus effect operative connection between the handles.

While the invention has been disclosed in accordance with the provisions of the patent statutes, it is to be understood that various changes in the structural details and modifications thereof may be made without departing from some of the essential features of the invention.

We claim as our invention:

1. In an enclosed circuit interrupter, a housing having an openable cover, a circuit interrupter unit having an oscillatable actuating handle mounted in said housing, an operating handle rotatably mounted on said cover for moving said actuating handle to actuate the interrupter, means providing a separable connection between said handles, said means being operable to establish an operative connection between said handles after the cover is closed irrespective of any difference of position of said handles, by manual movement of said operating handle to a position corresponding to that of said interrupter handle.
2. In an enclosed circuit interrupter, a housing having an openable cover, a circuit interrupter unit having a movable actuating handle mounted in said housing, a movable operating handle on said cover for moving said actuating handle to operate the interrupter, means providing a separable connection between said handles which is operable after the cover is closed to establish an operative connection between the handles by manually moving said operating handle to a position corresponding to that of said actuating handle.
3. In an enclosed circuit interrupter, a housing having an openable cover, a circuit interrupter having an actuating handle movable to "on" and "off" positions mounted in said housing, an operating handle on said cover movable to corresponding "on" and "off" positions to operate the interrupter, means providing a separable connection between said handles which when the cover is closed and the handles are in non-corresponding positions is operable to effect an operative connection between said handles upon manual movement of said operating handle to a position corresponding to that of said interrupter handle.
4. In an enclosed circuit interrupter, a housing having an openable cover, a circuit interrupter 50 having a movable actuating handle mounted in said housing, a movable operating handle on said cover for moving said actuating handle to operate the interrupter, means providing a separable connection between said handles comprising an element movable with one of said handles and engageable with the other handle, said cover being closable when said handles are in non-corresponding position, and said element being yieldable to permit operative engagement thereof by manual movement of said operating handle to a position corresponding to that of said actuating handle after the cover is closed.
5. In an enclosed circuit interrupter, a housing 55 having an openable cover, a circuit interrupter having a movable actuating handle mounted in said housing, a movable operating handle on said cover for moving said actuating handle to operate the interrupter, means providing a separable connection between said handles, said means comprising interengageable elements carried respectively by said operating handle and said actuating handle, one of said elements having means for causing it to yield and snap into 70
6. In an enclosed circuit interrupter, a housing having an openable cover, a circuit interrupter having a movable actuating handle mounted in said housing, a movable operating handle on said cover for moving said actuating handle to operate the interrupter, means providing a separable connection between said handles comprising interengageable elements carried respectively by said operating handle and said actuating handle, and means for causing said elements to operatively engage to effect an operative connection between said handles when the operating handle is manually moved to a position corresponding to that of said actuating handle after the cover is closed.
7. In an enclosed circuit interrupter, a housing having an openable cover, a circuit interrupter having a movable actuating handle mounted in said housing, a movable operating handle on said cover for moving said actuating handle to operate the interrupter, means providing a separable connection between said handles comprising an element movable with said operating handle interengageable with an element movable with said actuating handle, said element movable with said actuating handle being yieldable away from said cover to allow said elements to operatively engage to effect an operative connection between said handles when said operating handle is manually moved to a position corresponding to that of said actuating handle after said cover is closed.
8. In an enclosed circuit interrupter, a housing having an openable cover, a circuit interrupter having a movable actuating handle mounted in said housing, a movable operating handle on said cover for moving said actuating handle to operate the interrupter, means providing a separable connection between said handles, said means comprising an element movable with said operating handle and an element operable by said actuating handle, one of said elements having a recess for receiving the other element to effect operative connection of said handles, said elements being relatively yieldable away from each other to permit relative movement of said elements and engagement of said other element in said recess when the operating handle is moved to a position corresponding to that of said actuating handle after the cover is closed.
9. In an enclosed circuit interrupter, a housing having an openable cover, a circuit interrupter having a movable actuating handle mounted in said housing, a movable operating handle on said cover for moving said actuating handle to operate the interrupter, means providing a separable connection between said handles, said means comprising a projection carried by said operating handle and an element connected to said interrupter handle for movement with said interrupter handle, said element having a recess for receiving the projection of said operating handle to effect operative engagement of said handles and having inclined surfaces on opposite sides of said recess, said element being resiliently yieldable away from said cover to permit the projection on said operating handle to move along either of said inclined surfaces and 75 into said recess when said operating handle is

manually moved to a position corresponding to that of said actuating handle after the cover is closed.

10. In an enclosed circuit interrupter, a housing having an openable cover, a circuit interrupter having a movable actuating handle mounted in said housing, a movable operating handle on said cover for moving said actuating handle to operate the interrupter, means providing a separable connection between said handles, said means comprising a projection carried by said operating handle and an element secured to said actuating handle for movement with said actuating handle, said element having a recess for receiving the projection on said operating handle to operatively connect said handles and having inclined surfaces on opposite sides of the recess, said element being yieldable away from the cover and biased against the projection to permit said projection to move along either of the inclined surfaces and into said recess when said operating handle is moved to a position corresponding to that of said actuating handle after the cover is closed.

11. In an enclosed circuit interrupter, a housing, a circuit interrupter having an oscillatable actuating handle mounted in said housing, a rotatable operating handle on said housing for moving said actuating handle to operate the interrupter, means providing a separable connection between said handles comprising an element secured to said interrupter handle for movement therewith said element having a slot therein, and a crank pin carried by said operating handle engageable in said slot to effect an operative connection between said handles, said element having inclined surfaces on opposite sides of said slot and said element being yieldable away from and biased against said pin.

12. In an enclosed circuit interrupter, a housing having an openable cover, a circuit interrupter having an oscillatable actuating handle mounted in said housing, a rotatable operating handle on said cover for moving said actuating handle to operate the interrupter, means providing a separable connection between said handles comprising an element connected to said actuating handle by a pivot pin extending transversely through said actuating handle, said element having a portion extending in the direction of movement of said actuating handle, said portion having a transverse slot therein and having inclined surfaces on opposite sides of the slot, a crank pin carried by said operating handle engageable in said slot for effecting an operative connection between said handles, and a spring biasing said element against the crank pin.

13. In an enclosed circuit interrupter, a housing having an openable cover, a circuit interrupter having an oscillatable actuating handle mounted in said housing, a rotatable operating handle on said cover for moving said actuating handle to operate the interrupter, an element connected to said actuating handle by a pivot pin extending transversely through said handle, said element having a portion provided with a transverse slot and with cylindrically arched portions on opposite sides of the slot, a crank pin secured to said operating handle engageable in said slot

to operatively connect said handles, and a spring biasing said element against said crank pin.

14. In an enclosed circuit interrupter, a housing having an openable cover, a circuit interrupter having a movable handle mounted in said housing, a movable operating handle on said cover for moving said interrupter handle to operate the interrupter, means providing a separable connection between said handles comprising an element connected to one of said handles having means for operatively engaging the other handle to effect operative connection of said handles, said engaging means being yieldably compressible to permit operative engagement to be established after the cover is closed even though said handles are in non-corresponding positions, by manual movement of said operating handle to a position corresponding to that of said interrupter handle.

15. In an enclosed circuit interrupter, a housing having an openable cover, a circuit interrupter having a movable actuating handle mounted in said housing, a movable operating handle on said cover for moving said interrupter handle to operate the interrupter, means providing a separable connection between said handles, said means comprising an element connected to one of said handles having opposed inclined portions for operatively engaging the other handle, said opposed portions being yieldably compressible by said other handle to permit operative engagement to be established when said operating handle is manually moved to a position corresponding to that of said interrupter handle after the cover is closed.

16. In an enclosed circuit interrupter, a housing having a hinged cover, a circuit interrupter having an oscillatable handle mounted in said housing, a movable operating handle rotatably mounted on said cover for moving the interrupter handle to operate the interrupter, means providing a separable connection between said handles comprising an element connected to one of said handles having opposed inclined portions for operatively engaging the other handle, said opposed portions being yieldably compressible by said other handle to permit operative engagement to be established after the cover is closed, irrespective of the difference of position of said handles, by movement of the operating handle to a position corresponding to that of said interrupter handle.

17. In combination, a housing having an openable cover, a circuit interrupter having a movable actuating handle mounted in said housing, a movable operating handle on said cover for moving said interrupter handle to operate the interrupter, means providing a separable connection between said handles comprising an element connected to one of said handles having opposed portions for engaging the other handle, said portions being yieldably compressible by said other handle to permit operative engagement thereof after the cover is closed, by movement of the operating handle to a position corresponding to that of said interrupter handle.
